Inventor

David J. Cohen
By his Attorney,
F. J. Jordon, F. J. Jordon & Son,

UNITED STATES PATENT OFFICE.

DAVID J. COHEN, OF COLUMBUS, MISSISSIPPI, ASSIGNOR OF TWO-THIRDS TO
BENJAMIN G. CHAPMAN AND PATTERSON BAIN, OF ST. LOUIS, MISSOURI.

DESIGN FOR A BADGE OR MEDAL.

SPECIFICATION forming part of Design No. 21,411, dated March 22, 1892.

Application filed January 20, 1892. Serial No. 418,716. Term of patent 7 years.

To all whom it may concern:

Be it known that I, DAVID J. COHEN, a citizen of the United States, residing at Columbus, in the county of Lowndes and State of Mississippi, have invented and produced a new and original Design for Badges and Charms, of which the following is a specification, reference being had to the accompanying drawings, showing a part thereof.

10 In the drawings, Figure 1 shows one side of a badge or charm embodying my new design. Fig. 2 shows the opposite side of said badge or charm, the ornamentation of which is somewhat different from the opposite side and Fig. 3 is a cross-section taken through the same.

15 The leading feature of my design consists in a circular disk having central depressions at each side, said depressions being provided each with an emblem, as shown.

20 Referring to the drawings, 1 represents the badge or charm, which is of circular shape in outline and in cross-section, as shown. The surface of the body portion of the disk is similar on both sides, referring more especially to Fig. 3 of the drawings.

25 2 represents a rim, this being the thickest part of the badge, and adjacent to said rim are formed two annular depressions 3, which

are oppositely located upon both sides of the badge. Adjacent to said depressions 3 are two circular depressions 4, which are likewise oppositely located. Formed in one of the annular depressions 3, and upon one side of the badge is a series of stars. Within one of the depressions, referring especially to Fig. 1, are placed the emblems, as shown. The circular depression 4, formed in the said badge opposite to the one previously described and shown in Fig. 2, is provided with another emblem, the said depression forming a background for the said emblem.

30 5 represents a milled surface provided at the outer edge of each of the depressions 3, which gives a further ornamental appearance to the said badge.

35 6 represents a suspending device, which is located upon the edge of the badge.

40 Having fully described my invention, what I claim is —

45 The design for badges and charms, substantially as herein described and shown.

50 In testimony whereof I affix my signature in presence of two witnesses.

DAVID J. COHEN.
